UNITED STATES PATENT OFFICE.

WINFIELD H. YOST, OF MONTREAL, QUEBEC, CANADA.

DRAFT-RIGGING FOR RAILWAY-CARS.

1,265,414.

Specification of Letters Patent. Patented May 7, 1918.

Application filed January 7, 1911. Serial No. 601,430.

To all whom it may concern:

Be it known that I, WINFIELD H. YOST, a citizen of the United States, residing in Montreal, Province of Quebec, and Dominion of Canada, have invented certain new and useful Improvements in Draft-Rigging for Railway-Cars, of which the following is a description.

The object of my invention is to provide a draft rigging for railway cars having suitable spring and lever mechanism for yieldingly connecting the draw-bar with the draft timbers whereby the application of force will meet with a yielding resistance, and the recoil, when force is removed, will be reduced to a minimum.

A further object of my invention is to provide a rigging or draft gear having as few parts as possible, in which superimposed levers are employed, so constructed that the movement of the levers in relation to each other will be made positive; the levers being guided in their return movement to normal position; said lever mechanism being so constructed as to prevent any tendency on their part to spread the sills of the car. A further object of my invention is to provide a rigging wherein all the forces are induced to act in straight lines parallel with the center line and sides of the car, together with their other advantages, as will more fully appear from the following detailed description.

In the drawing:

Figure 1 is a horizontal central sectional view of my improved rigging, looking downwardly.

Fig. 2 is a longitudinal vertical sectional view taken on the line *a*—*a* of Fig. 1, with the yoke being shown in elevation.

Fig. 3 is a vertical sectional view taken on the line A—B of Fig. 2.

Fig. 4 is a perspective view of two of the levers shown in position to be assembled or placed on each other.

1, 1 are the draft members or sills of the car to which the cheek plates 2, 2 are properly secured. These cheek plates are provided at both ends with the draft lugs 3, 3' and 3'', 3''. The cheek plates may be of any suitable construction, but I prefer to from them as illustrated in Fig. 1, with the ends adjacent to the draft-lugs, bowed or bent outwardly so as to provide a narrower space between them for the reception of the gearing, as clearly illustrated, and for the

purpose hereinafter set forth. I provide a member or casing 4 having one end thereof open; both ends of the casing or member being provided with the lugs 5 and 6. 60 Mounted within the casing 4 are the concentric springs 7 and 8, which bear against the closed end of the casing, while the other ends thereof take against the bearing plate 9. Adjacent to the one end of the casing 65 4, namely, the open end thereof, I mount the superimposed levers 10 and 11 which are preferably made of the construction more clearly illustrated in Fig. 4. I have illustrated the rigging as provided with two 70 sets or pairs of levers 10 and 11, as clearly shown in Fig. 2, with the inner ends of the levers provided with vertically extending lugs 12 and 13, respectively; the contacting faces of the respective levers of the 75 different pairs being also provided with the ribs or flanges 14 and 15, respectively, at a point intermediate of the ends of the levers, see Fig. 4. The casing 4 with its springs 7 and 8 and bearing plate 9, together with the superimposed levers 10 and 11 are mounted within the yoke 16 which is suitably secured to the draw-bar 17, to which the coupler, not shown, is secured. A follower-plate 18 is inserted intermediate of 80 the superimposed levers and the yoke and is adapted to have bearing against the draft-lugs 3, 3' when a buffing force is applied to the mechanism as will be hereinafter set forth. As previously described the cheek 85 plates are preferably formed so as to allow for but little lateral movement to the casing 4, as clearly shown in Fig. 1, this being accomplished by forming the cheek plates with the outwardly bent portions adjacent 90 the lugs 3 and 3'.

When the levers are assembled the lugs 12 and 13 will bear against the narrower sides of the correlated or adjacent levers, while the ribs or flanges 14 and 15, which are 100 preferably formed arcuated, abut against each other and control the movement of the levers in both directions. The levers are superimposed by bringing the adjacent or correlated faces of the two levers shown in 105 Fig. 4, together. The ribs or flanges 14 and 15 will prevent any transverse movement of the levers, while the lugs 12 and 13 will cause the levers to interlock at the extreme point of their movement or travel in one 110 direction, and while the levers are at rest or in normal position the lugs will prevent fur-

ther relative movement in the other direction.

The operation of the draft rigging when force is applied to pull or move the car to the left, as shown in Fig. 1, will cause the tail strap or yoke 16 to force the follower-plate 18 against the inner ends of the superimposed levers 10 and 11, and cause said levers to move toward the left against bearing plate 9 and the action of springs 7 and 8. When the superimposed levers are in normal position, their outer ends will not be in contact with the end of the casing, but will be a little distance away from the end so as to allow for the free movement of the spring before the ends of the levers contact with the casing. If this movement is continued the outer ends of the levers 10 and 11 will contact with the flange or lugs 6 on the casing 4. This flange or lug 6 will act as a fulcrum point for the levers and cause them to rotate in the direction of the pull, that is, toward the left; the levers being allowed to rock about the fulcrum point 6, should the force continue, until the lugs 12 and 13 on the inner ends thereof interlock and prevent a further rocking of the levers. During the rocking of the levers as just described, the follower-plate 18, taking against the outer sides of the levers, will, through the action of the yoke 16, force the casing 4, through the contact caused by the outer ends of the levers, to the left, until the lugs or flanges 5 on the casing abut against the draft-lugs 3', 3'. During this movement of the levers there would be a tendency for them to slide transversely over one another; this action however is prevented by the contacting flanges or ribs 14 and 15. If the levers were allowed to slide over one another there would be danger of their becoming wedged and thus prevent the gearing becoming released when the force on the draw-bar is removed.

Should the application of force be in the opposite direction, that is, toward the right in Fig. 1, it will then be understood that the movement of the levers will be in the reverse direction, namely, the lugs 12 and 13 at the inner ends of the levers will contact with the side faces of the adjacent lever and lock the levers against relative movement in that direction and compel them to move bodily against the follower-plate 18. With the application of force toward the right, the draw-bar will take against the closed end of the casing 4 and compel it to move bodily toward the right, thereby forcing the lugs or flanges 6 against the outer ends of the levers 10 and 11 and move the interlocked levers as previously stated against the follower-plate 18, thereby compelling said follower-plate to take against the draft-lugs 3, 3', so that with the movement of the draft gear or rigging in either

direction, all of the forces will be substantially in a straight line parallel with the sides and center line of the car.

The levers with their respective lugs are so formed that when the levers are moved 70 against the springs, the lugs 12 and 13 will interlock at a safe margin beyond the limit of compression of the springs, and thus prevent the levers being drawn or wedged in the casing. 75

At the extreme travel of the gear toward the left, the levers are made to give a safe bearing on the flange or lug 6 of the casing 4, while the bearing of the follower plate 18, through the action of the coupler or 80 yoke thereon, will be very close to the fulcrum point or ends of the levers. This will cause all the forces to act in parallel lines and prevent any spreading of the sills 1, 1.

Carriers 19 are employed for securing the 85 sills 1, 1, together, and are preferably made trough shaped to extend underneath the yoke from sill to sill, as clearly shown in Figs. 2 and 3; the carriers being secured to the sills in any suitable manner. These carriers not only form ties for holding the sills with their cheek plates at a positive distance apart, but also carry the yoke 16 which in turn carries the entire draft gear. 90

The draft gear is assembled in the following manner:—The springs 7 and 8, where concentric springs are employed, are inserted in the casing 4, and the casing, together with the superimposed levers 10 and 11 is then placed in the yoke 16 with the bearing plate 9 interposed between the springs and the levers; the follower plate 18 is then inserted intermediate of the yoke and the levers; the respective parts being suitably held in proper relation through the action of the 100 springs, until the yoke, which has been properly secured to the draw-bar 17 is placed between the cheek plates; the yoke with the assembled parts being so placed as to bring the flange or lug 5 on the casing and the 110 outer ends of the levers between the cheek plates intermediate of the draft-lugs 3 and 3'; it is understood of course that the cheek plates have previously been riveted or secured to the center sills 1, 1 of the car. 115 After the mechanism has been thus assembled and put into place the carriers 19 are bolted or otherwise secured to the sills as previously described, thereby completing the application of the gear or draft rigging. 120

It is apparent from the foregoing description that but one set of levers, and but one follower plate is necessary in my improved draft rigging, thereby greatly simplifying 125 the construction.

Furthermore, the construction described may be varied in certain minor details, without departing from the spirit of my invention, as for example, a different construction 130

of spring may be employed instead of using concentric springs as shown. I do not wish to be understood therefore as limiting myself to the exact construction illustrated, but what I claim as my invention and wish to secure by Letters Patent is:—

1. A draft rigging having draft-lugs secured at opposite ends of the draft rigging, a member arranged between the draft-lugs and adapted to engage with one set of said lugs, levers arranged between the end of said member and the other set of said lugs and yieldingly held in normal position, and co-acting surfaces on adjacent faces of the levers whereby the levers will be held against any movement lengthwise of one another.

2. A draft rigging having a set of draft lugs at both ends of the rigging, a member longitudinally movable between the draft-lugs and adapted to engage with one set of said lugs, superimposed levers arranged between the end of said member and the other set of said draft-lugs, said levers being arranged to rotate about the end of said member, and coacting surfaces on the levers whereby movement of the levers lengthwise of one another is prevented.

3. A draft rigging for cars comprising draft-lugs, a hollow member, levers arranged at one end of the member and adapted to rotate about said end and into the member, spring-mechanism located in said member and bearing against the inner ends of the levers, said levers being provided with abutting surfaces on their correlated faces whereby relative transverse movement is prevented and a follower plate engaging said levers.

4. A draft rigging for cars consisting of two sets of draft lugs secured to the draft timbers of the car, an open ended hollow

cylindrical member provided with protruding portions at both ends thereof, the protruding portions at the one end of said member being arranged to engage with the one set of said draft lugs, levers arranged adjacent to the open end of said member and adapted to have engagement with the protruding portions on the adjacent end of said member, spring mechanism intermediate of the levers and the closed end of said member, a follower-plate arranged at the opposite side of said levers and adapted to engage the other set of draft lugs, and a draw-bar extension arranged about the member, levers, and follower-plate.

5. A draft rigging for cars consisting of two sets of draft lugs secured to the draft timbers of the car, a hollow cylindrical member open at its one end and provided with protruding portions at both ends thereof, the protruding portions at one end being arranged to engage with one set of said draft lugs, levers arranged adjacent to one end of said member and arranged to engage with the protruding portions on the adjacent end of said member, spring mechanism intermediate of the closed end of said member and said levers, the levers being provided with protruding portions whereby independent movement of the levers in a direction lengthwise of the rigging beyond a predetermined point is prevented, a follower-plate arranged on the opposite side of said levers and adapted to engage with the other set of said draft lugs, and a draw-bar yoke extending about the member, the levers, and the follower plate.
